(57) **CLAIM**

We claim the ornamental design for an accessory clip for a mobile electronic device, as shown and described.

DESCRIPTION

FIG. 1 is a front isometric view of an embodiment of an accessory clip for a mobile electronic device with a mobile electronic device and an auxiliary lens shown in dashed lines for environmental purposes.

FIG. 2 is a rear isometric view of the accessory clip for a mobile electronic device of FIG. 1 with the mobile electronic device and an auxiliary lens shown in dashed lines for environmental purposes.

FIG. 3 is a front isometric view of the accessory clip for a mobile electronic device of FIG. 1.

FIG. 4 is a rear isometric view of the accessory clip for a mobile electronic device of FIG. 1.

FIG. 5 is a front elevation view of the accessory clip for a mobile electronic device of FIG. 1.

FIG. 6 is a rear elevation view of the accessory clip for a mobile electronic device of FIG. 1.

FIG. 7 is a right side elevation view of the accessory clip for a mobile electronic device of FIG. 1.

FIG. 8 is a left side elevation view of the accessory clip for a mobile electronic device of FIG. 1.

FIG. 9 is a top plan view of the accessory clip for a mobile electronic device of FIG. 1; and,

FIG. 10 is a bottom plan view of the accessory clip for a mobile electronic device of FIG. 1.

The broken lines in the figures illustrate an illustrative mobile electronic device and auxiliary lenses and are for the purpose of illustrating environmental structure and form no part of the claimed design. The remaining broken lines in the figures illustrate bounds of the claimed design and form no part thereof.
